UNITED STATES PATENT OFFICE.

EDWIN G. LANG, OF BAYSIDE, NEW YORK, ASSIGNOR TO THE E. G. LANG MANUFACTURING COMPANY, OF NEW YORK, N. Y., A CORPORATION OF NEW YORK.

FOLDED INDEX-STRIP MACHINE AND PROCESS.

Application filed September 6, 1921. Serial No. 498,791.

To all whom it may concern:

Be it known that I, EDWIN G. LANG, a citizen of the United States, residing at Bayside, Long Island, in the county of 5 Queens and State of New York, have invented certain new and useful Improvements in a Folded Index-Strip Machine and Process, of which the following is a specification.

My invention relates to an improvement 10 in a process of making index tabs and the machine for carrying out such process.

Index tabs have heretofore been made by hand, and the manual process was long and tedious and necessarily expensive because of 15 the large amount of labor involved. My method and device have solved this problem by furnishing an automatic method of manufacturing index tabs and a machine for carrying out such process which will turn 20 out per day a volume of tabs greater than could heretofore be made by a large number of operators by hand in a day, and such machine requires only one operator, and then only occasionally to renew the supplies and 25 to set up the machine in operation and stop it.

Referring to the drawings Figure 1 is a front elevation showing the entire length of the machine; Figure 2 is a top plan view 30 of the same; Figure 3 is an end view looking in from the left hand end of Fig. 1; Figure 4 is a top plan view of the product; Figure 5 is a cross-sectional view of Fig. 4 on the line 5—5; Figure 6 is a detail of part 35 of the guideway, which is broken away, and the guide arm; and Figure 7 is a vertical sectional view on the line 7—7 in Fig. 3. Fig. 8 is a vertical sectional view on the line 8—8 in Fig. 6.

40 In the drawings 10 is a table top which is rigidly secured to standards 11, and the standards 11 are rigidly secured together by means of the longitudinal connecting rods 12. To the table top 10 is rigidly secured 45 a motor 13 of usual construction which is adapted to be driven by electric power which is not shown hereon, and in said motor 13 is mounted a shaft 14 which is driven thereby. On the outer end of the said shaft 14 is a 50 worm gear 15.

A sub-frame 16 is rigidly secured at 55 17 to the table top 10. In the sub-frame 16 is mounted a shaft 18 in suitable bearings so that it will rotate freely, and on the outer end of said shaft 18 is rigidly mounted a

pinion 19 so that it will engage with the worm gear 15. A gear 20 is also rigidly mounted on the shaft 18 so that it rotates therewith. A second shaft 21 is mounted in suitable bearings in the sub-frame 16 so that 60 it will rotate freely therein, and on the outer end of said shaft is rigidly secured a gear 22 which is adapted to mesh with gear 20 on shaft 18 and rotate therewith. A second gear 23 is also rigidly mounted on shaft 21 65 just inside of the gear 22 and travels with the rotation of said shaft 21. A third shaft 24 is mounted in guide blocks 25, which also act as bearings, which blocks 25 move in guideways 26 of sub-frame 16, the relative 70 position of which can be changed by means of bolts 27 over which are springs 28 adapted to keep the shaft 24 under spring pressure thereby. The bolt members 24 are mounted in plates 29 which are bolted at 75 30 to the two upper ends of the sub-frame 16. On the outer end of the shaft 24 is rigidly secured a gear 31 which is adapted to mesh with gear 23 on shaft 21.

A pressure roller 32 is rigidly secured to 80 the shaft 24 so that it rotates therewith, and a second pressure roller 33 is rigidly secured to the shaft 21 so that it rotates therewith and also with the roller 32 as they are arranged to press against each other under 85 pressure of springs 28. Said roller 33 is of sufficient width and has flanges 34 adapted to extend beyond and overlap the sides of the roller 32 as they rotate together.

An eccentric 35 is rigidly mounted on the 90 shaft 18 so that it rotates therewith and is adapted to contact with and rotate with a roller 36 which is loosely mounted on a block 37 which travels in a guideway 38, and which block 37 also carries rigidly secured thereto a 95 knife 39 and has a spring 40 mounted in the top thereon which keeps knife 39 normally in the lower position. The spring 40 is also mounted at its upper end to a rigid block 41 which is rigidly secured to the sub-frame 16, 100 and said block 41 also carries a stationary knife 42 rigidly secured thereto. A supporting bar 43 is mounted by means of pins 44 under spring pressure 45 on an outturned lip 46 rigidly secured to the block 37, so that 105 the supporting bar 43 readily yields under pressure.

At the opposite end of the table top 10 from the sub-frame 16 is a second sub-frame 47 which is rigidly secured at 48 to the 110

table top 10. A pair of moistening rollers 49 and 50 having absorbent surfaces are mounted on shafts 51 and 52, which shafts are loosely mounted in sub-frame 47 so that they rotate freely thereon, and so that said moistening rollers 49 and 50 contact with each other and turn together. A similar pair of moistening rollers 53 and 54 are mounted on shafts 55 and 56, which shafts are mounted in the sub-frame 47 so that they rotate freely. Said rollers 53 and 54 are rigidly mounted on shafts 55 and 56 and rotate therewith partially within water pans 57 and 58 which are rigidly secured to the sub-frame 47 and which pans have respectively covers 59 and 60 secured thereto with openings so that said pans 57 and 58 may be readily filled with water. A filler 92 is rigidly secured to the cover 60 for convenience in filling pan 58.

Pinion 61 is rigidly mounted on shaft 55 so that it rotates therewith, and pinion 62 is rigidly mounted on shaft 56 so that it rotates therewith. Pinion 63 is rigidly mounted on a shaft 93 which is mounted in the sub-frame 47 so that it rotates freely. Pinion 64 is rigidly mounted on shaft 24 and rotates therewith. A chain 65 is mounted so that it runs over pinions 61, 62, 63 and 64.

30 A guideway 66 is rigidly secured to a bracket 67, and said bracket 67 is rigidly secured by means of set screws 68 in an adjustable slot 69 to an upright 70 which is rigidly secured to the table top at 71.

35 The guideway 66 has a neck portion 72 adapted to form the material running therethrough to a position ready for folding. A post 73 is rigidly secured to the table top 10, and a guide arm 74 is rigidly secured to said post 73 by means of a bolt and wing nut 75. The guide arm 74 has a groove or lip member 76 which is adapted to guide into its proper position, before sealing, a core member 87 of the tab. A hinged tension member 77 is rigidly secured to the sub-frame 16 at 78, and the tension plate or hinge member 79 is held under tension by means of spring compression screws 80.

40 Outer material 88 for the tab, which is preferably gummed on the inside, is fed from a turntable 81 which is rotatably mounted on post 82 which is rigidly secured to the table top 10. A guide roller 83 is rotatably mounted on a post 84 which is rigidly secured to the table top 10, so that the outer material for the tab will roll over said roller in passing into the guideway 66. A core holder 85 is rotatably mounted on a bracket 86 which is rigidly secured to the table top 10 at 94 so that the core member 87 of the tab can be fed freely therefrom.

45 In setting up my machine for the operation it is necessary to do it manually. The operator first draws the end of the roll of outer material 88 around the roller member

83 into and through the guideway 66. The core member 87 must then be run through between moistening rollers 49 and 54 through the guideway 66, and the two ends of the members 87 and 88 are then run through the guideway 66, then 87 must be run through the groove 76 of the guide arm 74. A pry arm 89 pivoted on the sub-frame 16 at 95 is then swung around so that a wedge 90 will operate to lift the tension plate 79 so that the ends of 87 and 88 can be run through the tension member 77 until they project between the compressor rollers 32 and 33.

50 The machine is now set up ready for the operation, and by turning on the power the shaft 14 is set in motion, which motion is transmitted through the worm gear 15 and pinion 19 to the shaft 18 which turns the gear 20, which in turn drives the gear 22 in the opposite direction. This turns the shaft 21 and also the gear 23 thereon which meshes with gear 31, and which is turned thereby.

55 The turning of gear 31 sets the shaft 24 in operation, and the pressure roller 32 which is mounted thereon. Pressure roller 33 travels with the shaft 21 on which it is mounted. The pinion 64 travels with shaft 24 on which it is mounted, and the chain 65 is thereby set in motion so that the chain 65 travels over pinions 61, 62 and 63, as indicated, and they are thereby set in operation.

60 As the pinion 61 rotates the shaft 55 and the moistening roller 53 carried thereon are rotated, and the roller 53 picks up water from the pan 57 on its absorbent face and transfers a portion of the same to moistening roller 50 which is in contact with roller 53 and rotated thereby. Roller 50 in turn transfers some of the water carried thereon to moistening roller 49 with which it is also in contact and so causes the same to rotate as it rotates. Moistening roller 54 is set in motion by the rotation of the pinion 62 through the shaft 56 and thereby picks up a certain amount of water from the pan 58.

65 The moistening rollers 49 and 54 as they rotate coat the core member 87 with moisture on both sides of the same as 87 passes between them. The outer material 88 having a coating of suitable glue or other adhesive on the inside or exposed surface as it runs through the guideway 66 closes down over the core 87 as it runs through the neck 72, and the edge of 87 is pushed into contact with the folded edge of 88 on the inside thereof by means of lip 76, and as 87 and 88 pass through tension member 77 they are thereby partially sealed together and held firmly together under a back tension as they are drawn through this operation by the pull of the compression rollers 32 and 33.

70 A suitable number of teeth of the gears 20 are cut out so that in the rotation of the gear 20 this cut out portion 91 is in alignment and functions with the eccentric portion of the 75

eccentric 35 on shaft 18. The gear 22 also has a cut out portion 96 which is sufficient to permit the cut out portion 91 to slide by as shaft 18 is always in rotation, and therefore gear 28 continues to rotate continuously. The construction permits gear 22 and all of the parts connected therewith to come to a full stop during the rotation of gear 20 through the cut out portion 91 as it passes the cut out portion 96 of gear 22, and thereby the movement of the members 87 and 88 through the compression rollers 32 and 33 is stopped so that the tab completed and projecting from said compression rollers is cut by knife 39 which is operated by the eccentric 35, as it finishes up block 37 on each rotation of 35.

It is thus seen that the length around the gear 22 from one side of the cut out 96 to the other side of the cut out will determine the rotation of shaft 21 which in turn controls the rotation of shaft 24 and the two compression rollers 32 and 33 thereon. It is therefore necessary to only change this gear 22 to obtain a different length of tab to be cut.

My machine and process are adapted to be used in the making of index tabs, hinged binders, or other articles of a similar nature common to the book binding art. Cloth, leather, paper or other suitable material may be used for the outside member 88, and any suitable material may be used for core member 87. I do not confine myself to the materials suggested or to the exact form of the machine shown or the process described, as I intend to cover the many variations in all of these which may be apparent to those well versed in the art.

Throughout the application the term tab has been used, but the article made by this process and machine are merely strips which may be used as tags, tabs or for any suitable use for which folded index strip material may be used. The gumming of the outside member may also be confined to the center portion so that the folded strip will be ungummed on the unstuck inside portion and the back or exterior portion when folded on the outside member may be lettered or printed in any desired manner, and the length of strip cut varied accordingly.

I claim:

1. In a machine the combination of a series of gears adapted to operate a pair of pressure rollers, means for folding an outside member over a core member, means for feeding said folded members, means for preparing the sticking of said members together, means for sticking said members together, and automatic means for cutting the strips when so stuck into the desired lengths.

2. In a machine the combination of a

series of gears adapted to operate a pair of pressure rollers, means for folding an outside member over a core member, consisting of a guideway and guide arm and a tension member, means for feeding said folded members, means for preparing said members for sticking them together, means for sticking them together, and means for cutting the strips when so stuck into the lengths desired. 70

3. In a machine the combination of a series of gears adapted to operate a pair of pressure rollers, means for folding an outside member over a core member, consisting of a guideway and guide arm and a tension member, means for feeding said folded members, means for preparing said members for sticking them together, consisting of moistening rollers between which the core member passes so that it is moistened on both sides thereby moistening the gummed inner surface of the outside member, means for sticking them together, and means for cutting them into the desired lengths. 75

4. In a machine the combination of a series of gears adapted to operate a pair of pressure rollers, means for folding an outside member over a core member consisting of a guideway and guide arm and a tension member, means for feeding said folded members, means for preparing said members for sticking them together, consisting of moistening rollers between which the core member passes so that it is moistened on both sides thereby moistening the gummed inner surface of the outside member, means for sticking them together, consisting of said tension member and the pressure rollers and means for cutting them into the desired lengths. 90

5. In a machine the combination of a series of gears adapted to operate a pair of pressure rollers, means for folding an outside member over a core member consisting of a guideway and guide arm and a tension member, means for feeding said folded members, means for preparing said members for sticking them together, consisting of moistening rollers between which the core member passes so that it is moistened on both sides thereby moistening the gummed inner surface of the outside member, means for sticking them together, consisting of said tension member and the pressure rollers and means for cutting them into the desired lengths, consisting of a knife which is mounted so that it is operated by the rotation of an eccentric each time that the main gear is passing cut out portions on said gear and on the gear with which it meshes in the series first mentioned. 105

6. In a folded strip machine the combination of a table, an electric motor secured thereto, a sub-frame also secured to said table in which is mounted a series of gears driven by said motor on shafts carrying a 110

pair of compression rollers, cut outs on the main driving and driven gears, an eccentric on the same shaft with said main driving gear adapted to raise a knife under normal downward pressure and slidably mounted on said sub-frame, during each passing of said gear cut outs, a series of moistening rollers mounted in a second sub-frame secured to said table driven by a chain drive running over a pinion on a driven shaft in the first sub-frame and also over a series of pinions mounted on the same shafts with the said moistening rollers, a guideway and guide arm mounted on posts secured to said table, a tension member secured to said first sub-frame, and a turn table and feed holder independently secured to said table from which the outside member and core member respectively are fed.

7. The process of making folded index strips continuously which consists in placing a core member moistened on both sides in-

side of an outside member gummed on the inside, sticking the outside member to both sides of the core member and cutting the strip to the length desired.

8. In a machine the combination of a series of gears adapted to operate a pair of pressure rollers, means for folding an outside member over a core member, consisting of a guideway and guide arm and a tension member, means for feeding said folded members, means for preparing said members for sticking them together, means for sticking them together, and means for cutting the strips when so stuck into the lengths desired, consisting of a knife which is mounted so that it is operated by the rotation of an eccentric each time that the main gear is passing cut out portions on said gear and on the gear with which it meshes in the series first mentioned.

In testimony whereof I affix my signature.
EDWIN G. LANG.
